UNITED STATES PATENT OFFICE

2,568,683

REGROOVING TOOL

Ernest J. Mayher, Kiwanis Lake, Ohio, assignor
to The Tremont Tool and Gage Company, Inc.,
Cleveland, Ohio, a corporation of Ohio

Application August 25, 1948, Serial No. 46,035

1 Claim. (Cl. 77—2)

1

This invention relates to re-grooving tools and more particularly to a tool for grooving or re-grooving the annular walls of a cylinder, such as an automotive distributor body.

It is an object of the present invention to provide a tool of the above named character which is of simple and sturdy construction and which in use will accurately groove or re-groove a cylinder due to the provision of means for adjusting and rigidly maintaining the cutters in adjusted position in the tool.

A further object of this invention resides in a grooving or re-grooving tool having a plurality of grooving cutters radially disposed in the tool and normally urged to a retracted position inwardly thereof, and means for feeding said cutters simultaneously radially outwardly of the tool.

Another object of the invention is the provision of a tool of this character which can be quickly applied to a cylinder, such as a distributor body, for a grooving operation.

Still another object is the provision of means whereby the cutters, while movable radially in the tool, will be maintained in proper cutting position with respect to each other and the cylinder during the grooving operation thus insuring a clean, even and precision grooving of the cylinder wall.

A still further object of this invention consists in the provision of indicating means whereby the extent of the cut being made may at all times quickly and easily be determined by the operator, thus eliminating unnecessary cutting or thinning of the cylinder wall.

Other objects and advantages of my invention will become more apparent as the following description of one embodiment thereof progresses, reference being made to the accompanying drawings, in which like reference characters are employed to designate like parts throughout the same.

In the drawings:

Figure 1 is a vertical central section through a tool embodying my invention and shown applied in use on a distributor casing or cylinder.

Figure 2 is a section taken on line 2—2 of Figure 1, and,

Figure 3 is a view taken in the direction of line 3—3 of Figure 1.

In carrying out my invention as illustrated in the drawings, I provide a tool which can quickly and easily be applied to a cylinder such as a distributor body in an automotive ignition system as shown in Figure 1. The distributor body 1 is grooved at 2 annularly along its inner wall

2

to receive and be operatively engaged by the rotating breaker assembly of the distributor.

Referring now more particularly to Figure 1 the tool comprises a base 3 having an axial opening 4, receiving the reduced end of the shaft 5 in axial alignment, the shaft and the base being securely welded together as at 6.

A body 7 having an internally threaded opening 8 axially aligned with the opening 4 is supported on the base 3, the bottom of the body being grooved concentrically, as at 9, and radially grooved at 10 for purposes which will presently appear.

Bolts 11 are provided to removably secure the base 3 and body 7 together.

The body 7 is formed with an upwardly extending central portion 12 through which the opening 8 extends there being a boss formed at 13. An outer collar having an upright portion 14 and a lateral flange portion 15 is fitted over the body as shown in Figure 1. This collar is adapted to carry a plurality of clamping members 16 for clamping the distributor casing or cylinder 1 in the tool. These clamps are channel or C-shaped and are pivotally supported at 17 on the brackets 18 which are in turn bolted or secured to the side wall of the body portion 12. Each clamp 16 is provided with an adjustable clamping screw 19 adapted to engage and grip the under surfaces of the article 1 as illustrated in Figure 1.

The under portion of the collar flange 15 is formed with an annular rib 20 abutting on one side with the outer wall 21 of the body portion 7, the rib being within the circumference of the flange 15 to provide a seat 22 for the upper end 23 of the article 1 as illustrated in Figure 1.

An upstanding rib 24 is formed on the collar, and between this and the base 13 an indicating plate 25 is positioned and secured to the portion 12 of the body 7 by means of the screws 26.

A knurled knob 27 is formed on the upper end of the screw 28 for turning and adjusting the screw axially in the body 7. The screw 28 has a flat side 29 to prevent relative rotational movement between it and the indicating pointer 30 which is carried on the screw. This pointer is urged downwardly on the screw by means of a coil spring 31 to lie flat upon and to scan the upper surface of the plate 25 upon which are marked graduations or other indicia 32 relating to the feed of the cutters carried between the body 7 and the base 3.

A plurality of cutters 33 are radially arranged between the base 3 and the body 7 to move longitudinally in the radial grooves or slots 10, and

rear ends of said cutters having downwardly inclined walls 34 for engagement by the conical end 35 of the screw 28 which is projected downwardly between the respective adjacent rear ends of the cutters. These ends of the cutters overlie the opening 4 in the base 3 and it will readily be seen that when the screw 28 is adjusted downwardly the cutters 33 will be forced radially outwardly to engage the groove 2 in the distributor body.

Of course, by means of the pointer 30 and indicia 32 the proper cutting depth may readily be determined. The cutters are first simultaneously fed outwardly to engage the groove 2 by adjusting the screw 28 and the reading on the scale 25 is noted. Then by turning the screw 28 to exert additional outward pressure on the cutters the article is ready for re-grooving.

It is to be noted that I have provided means for simultaneously and normally exerting a retracting force on the cutters. Such means may consist of an endless resilient member, such as an endless coiled spring 36, which is seated in the notches 37 formed in the cutters 33 and which is also seated in the annular groove 9 in the body 1. When the spring 36 is in such position it normally is under tension and exerts a force simultaneously urging the cutters radially inwardly toward the axis of the base 3. In feeding the cutters outwardly by rotating the screw 28 in one direction such feed is in opposition to the spring 36, and when the screw is rotated in an opposite direction the forces exerted by the spring 36 on the cutters act to retract the cutters inwardly of the tool.

In use, the tool may be applied to a distributor housing 1 as shown in Figure 1, the top of the housing abutting the rib 20 and the bottom wall of the flange 15. The clamps 16 are then adjusted and locked in the position shown by tightening the screws 19 against the bottom of the housing 1. The shaft 5 of the tool passes through the hub 40 and a split collar 41 is carried on the shaft 5 below the hub of the housing 1, the split collar being adapted to be clamped in a vise and when so clamped to grip the shaft 5 tightly. Then the member 14-15 carrying the clamps 16 and the article 1 to be re-grooved can be rotated by grasping the clamps 16 and spinning the same on the axis of the shaft 5 in a clockwise direction as seen in Figure 2. Another manner of imparting relative rotative motion between the cutters and the article 1 is to loosely mount the collar 41 on the shaft 5, holding the

assembly 14-15 and 16 against rotation, as in a vise, and applying a wrench or other tool to the lower end of the shaft 5 and then rotating the same.

5 After the cutters 33 have been adjusted in the groove 2 to effect the desired cut the article holding assembly and the cutter assembly may be relatively rotated in the proper direction to effect a re-grooving of the groove 2. To insure a 10 smooth and complete re-grooving operation the cutters 33 may be fed radially outwardly of the tool to an even greater extent by adjusting the screw 28 downwardly.

Various changes may be made in the details of 15 construction and arrangement of parts without departing from the spirit of the invention or the scope of the appended claim.

I claim:

20 A regrooving tool comprising a work holder, means pivotally suspended from said holder for removably clamping a work piece thereto, a rotatable cutter support carried by said work holder, said cutter support comprising a rotatable base on which regrooving cutters are supported, 25 a member carried by said support and having radially disposed cutter receiving channels opening from its under side and an axially disposed opening through said member, cutter adjusting means threaded into said opening and having a 30 conical inner end engageable with the inner ends of regrooving cutters, a plurality of regrooving cutters slidable radially of said support and along said channels between the base and said member, said cutters each having a transverse guide, and 35 a common resilient means associated with said guides and normally urging said cutters radially inwardly of said support to maintain said cutter inner ends constantly in contact with the inner conical end of said adjusting means.

40 ERNEST J. MAYHER.
